UNITED STATES PATENT OFFICE.

FRANK R. HOOD, OF STOCKTON, CALIFORNIA.

GRADER.

Application filed May 25, 1927. Serial No. 194,163.

This invention relates to improvements in graders.

The principal object of this invention is to produce a grader which is inexpensive to construct, and one having a large capacity.

Another object of this invention is to produce a grader wherein the upkeep will be small, due to the fact that the material being graded rides on the conveyer and therefore 10 there is no scratching or grinding as is present in rotary screens or shakers.

Another object is to produce a grader which will give more accurate grading.

Another object is to produce a grader which 15 will not injure the material being graded, as for instance, fruit and the like, as the danger of pinching is entirely eliminated.

A further object is to produce a grader wherein various grades or sizes may be 20 quickly changed.

A still further object is to produce a grader which will handle a variety of different materials by simply substituting different styles of grade chains.

25 Other objects and advantages will be apparent during the course of the following description.

In the accompanying drawings forming a part of this specification, and in which like 30 numerals are employed to designate like parts throughout the same,

Figure I is a top plan view of my machine partly broken away,

Figure II is a side elevation of Figure I,

35 Figure III is a fragmentary detail view showing the manner of connecting the links,

Figure IV is an end view of one of the center links,

Figure V is a side elevation of Figure IV,

40 Figure VI is a top plan view of Figure IV,

Figure VII is an end elevation of one of the under links,

Figure VIII is a top plan view of Figure VII,

45 Figure IX is a side elevation of one of the side links, and

Figure X is an end view of Figure IX.

In grading with an ordinary rotary screen, it often occurs that flat rocks or elongated 50 rocks enter the grader openings and clog the hole. This is due to the fact that the material within the grader is being tumbled around, which action causes a wearing of the grader.

55 I have sought to overcome these difficulties by providing a grader consisting of a plurality of chains having peculiarly shaped

links. These chains travel side by side between spaced pulleys and in such a manner that the distance between the chains increases from one end of the machine to the opposite 60 end of the machine.

In the accompanying drawings wherein for the purpose of illustration is shown a preferred embodiment of my invention, the numerals 5 and 6 refer to supports for shafts 65 7 and 8. The shafts 7 and 8 each have thereon a plurality of sprocket wheels as shown at 9 and 11, respectively.

By viewing Figure I, it will be noted that the sprocket wheels 11 are spaced from each other a distance greater than the sprocket 70 wheels 9. The result being that as the chains in passing from one end of the machine to the other end draw away from each other in travelling along the top of the machine, and 75 then draw toward each other in travelling along the bottom of the machine.

The chains referred to comprise a plurality of peculiarly constructed links, which links will be hereinafter termed the middle links, 80 the under links and the side links.

Referring now to Figure VI, it will be seen that I have illustrated one of the middle links which is provided with a plurality of inclined faces 12, 13, 14, 16, 17, 18, 19 and 85 21, all of which faces reach an apex at 22.

Formed upon the under side of the middle links designated as a whole by the numeral 15, are downwardly extending parallel webs 23 and 24. These webs have openings 26 90 therethrough for the reception of connecting pins as will be hereinafter described.

Referring now to Figure VII, it will be noted that the under links comprise two relatively flat surfaces 27 and 28, and two inclined 95 surfaces 29 and 31, which terminate in an apex 32. These under links are also provided with downwardly extending parallel webs as shown at 33 and 34, which webs are also provided with holes therein for the same purpose before described.

The side links as illustrated in Figures IX and X are provided with an inclined surface 36 which inclined surface reaches an apex at 37 and contains a vertical outer wall 38.

Projecting from the inclined surface 36 is an extension 39 having inclined surfaces 41 and 42. These side links are also provided with downwardly extending parallel webs 43 and 44. These webs are provided with openings therethrough for the reception of connecting links. As all of the links in

the chain are connected in a similar manner, but one connection of the chain will be described.

Referring to Figure III, I have shown a plurality of under links as the same would appear when viewed from the bottom. It will be noted that these links have their webs in alignment with each other and have interposed between each pair of links a connector block 46, which are of the same width as the distance between the adjacent walls of the webs.

At 47, I have shown U-shaped connector pins which extend through the webs 33 and 34 and also through the connector blocks 46. These bring the end of the connector pins at a point beneath the bottom of the under links so that cotter pins 48 may be introduced, which cotter pins are entirely protected against injury, as well as the possibility of their injuring any material being graded.

Assuming that a machine has been constructed in accordance with my invention as illustrated in Figure I and that the same is in operation, it will be readily seen that any material placed upon the grader will roll toward the rectangular-shaped openings formed between the overlapping links.

Material disposed upon the grader will therefore overlie one of these openings as for instance the opening A and assuming that we are grading oranges, if the opening A is of sufficient size to allow the orange to pass there-through, the same will be disposed in a trough 49 and conveyed to any definite point for packing.

Assuming that the orange is too large to pass through the opening A, it will travel with the conveyor until it reaches a position where the links have moved a sufficient dis-

tance apart to permit the orange to pass through the opening which we will consider the point B. At this point the orange will drop through the opening and into the trough 51.

In Figure I, I have shown hand wheels 52 for tightening the chains if desired. These tightening means are not necessary to the operation of my device however.

It is to be understood that the form of my invention herewith shown and described is to be taken as a preferred example of the same, and that various changes relative to the shape, size, material and arrangement of parts may be resorted to without departing from the spirit of the invention, or the scope of the subjoined claim.

Having thus described my invention, I claim:

In a grader of the character described, a pair of diverging chains adapted to travel in the same horizontal plane, said chains being constructed of links having a vertical outer wall and an inclined surface extending from the outer wall of said links to the inner wall thereof, a projection extending from each of said links, said extensions each having inclined surfaces diagonally disposed with relation to the direction of travel of the chains, a central chain comprising under links positioned between said first mentioned links, each of said under links comprising two relatively flat surfaces having their edges inclined with relation to the direction of movement of said chains and carrying thereon upwardly inclined surfaces, said inclined surfaces being parallel to the direction of travel of said chains.

In testimony whereof I affix my signature.

FRANK R. HOOD.
